ELECTRON GUN FOR CATHODE-RAY TUBES

Wesley H. Van Ornum, Chicago, Ill., assignor to
Rauland Corporation, a corporation of Illinois

Application September 1, 1950, Serial No. 182,774

3 Claims. (Cl. 313—85)

1

This invention relates to electron guns for cathode-ray tubes or the like, and more particularly to a novel supporting arrangement for the electrodes constituting an electron gun.

A conventional cathode-ray tube electron gun comprises a plurality of tubular electrodes, including first and second grids and an anode, arranged in predetermined mutually spaced relation to direct and control an electron beam originating at an indirectly heated cathode. It is customary practice to provide studs extending outwardly from each of the tubular electrodes at correspondingly spaced peripheral intervals, and to affix rigid insulating spacer-support members to longitudinally aligned studs in order to support the second grid and the anode from the first grid. To this end, the outwardly-extending studs are individually welded to the respective tubular electrodes; this welding operation is both time-consuming and costly.

It is the object of the present invention to provide a new and improved electron gun, for a cathode-ray tube or the like, in which the several electrodes are supported in a desired predetermined mutually-spaced relation in a simple and economical manner.

In accordance with the invention, an electron gun for a cathode-ray tube comprises first and second tubular electrodes. Outwardly-extending studs are supported by the respective first and second electrodes, at least one of the studs being in the form of an integral projection struck from one of the electrodes. A rigid insulating spacer-support member is affixed to the studs to support the two electrodes in predetermined longitudinally spaced relation with respect to each other.

The features of the present invention which are believed to be novel are set forth with particularity in the appended claims. The invention, together with further objects and advantages thereof, may best be understood, however, by reference to the following description taken in connection with the accompanying drawing, in the several figures of which like reference numerals indicate like elements, and in which:

Figure 1 is a fragmentary view, partly in section, of a cathode-ray tube comprising an electron gun constructed in accordance with the present invention;

Figure 2 is an elevational view, partly in section and taken in a direction at right angles to the showing of Figure 1, of the electron gun structure; and

Figure 3 is a plan view of one of the electrodes. As shown in Figure 1, a cathode-ray tube may

2

comprise an evacuated envelope 10 having an electron gun for directing a focussed electron beam to a fluorescent screen (not shown) provided at one end 11 of the envelope. The electron gun comprises three tubular electrodes 12, 13 and 14, conventionally designated the first grid, the second grid, and the anode respectively. A conductive coating 15 is applied to the inner wall of the envelope 10 to provide a field-free path for the electron beam in its progress from the electron gun to the fluorescent screen, and conductive coating 15 is maintained at a common potential with anode 14, by means of a plurality of resilient metal contacts 16. As best shown in Figure 2, a thermionic cathode 17, preferably of the indirectly-heated type, is supported within the first grid 12 by means of an insulating spacer 18.

Each of the electrodes 12, 13 and 14 is provided with a plurality of outwardly-extending studs 19, 20, and 21 respectively, and a pair of rigid insulating spacer-support members 22 and 23 are affixed to longitudinally aligned studs 19, 20 and 21 supported by the several electrodes. In this manner, the electrodes are maintained in a desired predetermined mutually-spaced relation, the second grid 13 and the anode 14 being supported by the first grid 12 which in turn may be held firmly within the evacuated envelope 10 by means of support members 24 (Figure 1) extending inwardly from the base of the tube.

In accordance with the invention, some or all of the studs 19, 20, and 21 are constructed as integral projections struck from the respective electrodes 12, 13, and 14. In order to obtain increased rigidity, it is preferred that the projections be folded or channeled as indicated in Figure 3. In this manner, the necessity of welding separate stud members to the electrodes is obviated.

The striking and channeling operations may readily be performed by automatic equipment by the use of properly cut dies, in order to render the fabrication of the electrodes feasible for large scale production. As indicated in Figure 3, a generally rectangular aperture 25 may be cut in the electrode cylinder, leaving the material intact at each end of the aperture. A cross-cut may be made at an intermediate position indicated by the dotted line 26, and the two ears thus formed may readily be bent up and channeled to form the finished studs 21.

It has been found that the provision of one or more apertures 25 in the tubular electrodes permits the formation of the desired stud configuration without detrimentally affecting the forma-

tion or focussing of the electron beam. Undesirable discontinuities in the electrostatic fields existing within the respective electrodes are substantially avoided so long as the total area of the removed material is small relative to the total circumferential area of the electrode.

While the illustrated embodiment employs a pair of oppositely disposed rigid insulating spacer-support members 22 and 23, it is, of course, possible and within the scope of the invention to provide three or more of such spacer-support members; in any event, it is preferred that the studs extending outwardly from the several electrodes be spaced at substantially equal peripheral intervals. In this manner, the rigidity of the composite structure against subsequent deformation in any direction is optimized.

The particular electron gun structure illustrated in Figures 1 and 2 is of the type in which the anode is laterally offset from the first and second grids, and the entire gun assembly is tilted slightly from the longitudinal axis of the tube. In this manner, ion elimination may be readily effected by providing a single external ion-trap magnet (not shown). The structure is specifically disclosed and claimed in the copending application of Willis E. Phillips et al., Serial No. 156,746, filed April 19, 1950, for "Electron Gun for Cathode-Ray Tubes," now Patent No. 2,596,508 issued May 13, 1952, and assigned to the present assignee. The present invention is of course equally applicable to electron gun structures in which the several tubular electrodes are maintained in accurate coaxial alignment.

While a particular embodiment of the present invention has been shown and described, it is apparent that various changes and modifications may be made, and it is therefore contemplated in the appended claims to cover all such changes and modifications as fall within the true spirit and scope of the invention.

I claim:

1. In an electron gun for a cathode-ray tube: first and second tubular electrodes; a stud supported by said first electrode and extending outwardly therefrom; at least one stud in the form of an integral projection struck from said second electrode and extending outwardly therefrom; and a rigid insulating spacer-support member

affixed to said studs to support said second electrode in predetermined longitudinally spaced relation with said first electrode.

2. In an electron gun for a cathode-ray tube: first and second tubular electrodes; a stud supported by said first electrode and extending outwardly therefrom; at least one stud in the form of a channeled integral projection struck from said second electrode and extending outwardly therefrom; and a rigid insulating spacer-support member affixed to said studs to support said second electrode in predetermined longitudinally spaced relation with said first electrode.

3. In an electron gun for a cathode-ray tube: a plurality of tubular electrodes including a first grid, a second grid, and an anode; a plurality of studs supported by said first grid and extending outwardly therefrom at substantially equal peripheral intervals; a plurality of studs supported by said second grid and extending outwardly therefrom at peripheral intervals corresponding to those of said first-mentioned studs; a plurality of studs in the form of integral projections struck from said anode and individually extending outwardly therefrom in substantial longitudinal alignment with corresponding studs supported by said first and second grids; and a plurality of rigid insulating spacer-support members individually affixed to longitudinally aligned studs supported by said first and second grids and by said anode.

WESLEY H. VAN ORNUM.
